United States Patent Office.

ISAAC H. NEWTON, OF GRAND RAPIDS, MICHIGAN.

Letters Patent No. 88,063, dated March 23, 1869; antedated March 10, 1869.

IMPROVEMENT IN DEVICES FOR TURNING LOGS IN MILLS.

The Schedule referred to in these Letters Patent and making part of the same.

To whom it may concern:

Know all men, that I, ISAAC H. NEWTON, of Grand Rapids, in the county of Kent, and State of Michigan, have invented a new and useful Improvement in the Apparatus Used for Handling Logs in Saw-Mills; and I do declare that the following is a true and accurate description thereof, reference being had to the accompanying drawings, and to the letters of reference marked thereon, and being a part of this specification.

Figure 1 is a sectional view of one side of my apparatus, with beam removed to show the mechanical construction of the cants.

Figure 2 is a plan view of that part of my apparatus which is beneath the floor of the mill, and fastened to the same.

The same letters indicate similar parts in each figure.

I obtained a patent for an apparatus for handling logs in saw-mills, March 19, 1867, and my present application is for an improvement on that apparatus; and

Its nature consists in the operation of the canting-lever, and the mechanism to attain this operation.

To enable others to better understand my improvement, I will describe the whole apparatus and its operation, confining myself, in the claims, to what I actually have improved, and not desiring to claim the whole apparatus.

The nature of my invention consists, specially—

First, in the reciprocating rod F, provided with shoulder G, operated by the hook-lever E, and actuating the canting-lever H, as will be more fully described hereafter.

Second, in the combination with the above of the cant I, when constructed and operating as will be described.

Third, in the device for lowering the cant I, consisting of lever K, trippers L, and pins M, as will be described.

Fourth, in the combination of the cants I, canting-levers H, shaft B, connecting-rods F, with shoulders G, shaft J, lever K, trippers L, and pins M, when arranged for the purposes that will be described.

I place the drum A, loosely sleeved, upon the shaft B, under the floor of the mill, which shaft is driven, at all times, by a proper belt from any convenient part of the machinery.

To the shaft B is rigidly keyed the clutch C, whose counterpart is secured to the adjacent end of the drum A, fastened around which is the cord D, passing over and along the upper timbers of the mill to a

point over the carriage, descending over a proper pulley, and terminating in a proper hook.

Near each end of the shaft B, are the cams E E, fixed to and rotating with the shaft.

F F are connecting-rods, provided with shoulder G, and engaging with the canting-levers H.

I is the cant which turns the log upon the carriage.

J is a shaft under the floor of the mill, upon one end of which is a lever, K.

Upon this shaft, and under the ends of the connecting-rods F F, are the trippers L L, which, when not in use, rest upon the pins M M.

Having thus designated the various parts of my apparatus, I will now proceed to describe the method of using the same, premising, however, that the clutch C is out of gear.

The log to be turned being on the log-way, immediately over the cant I, the point of the cant-hook being inserted into the side of the log next the saw, the drum A is thrown into gear with the clutch C, revolving with the shaft B, which winds the rope D around the drum A, causing the log to make one-fourth of a revolution, the toe of the cam E engaging with the shoulder G of the connecting-rod F, carrying it back, and causing it to raise the cant I, by means of the canting-lever H, to an angle of about forty-five degrees, thus causing the log to slide forward upon the carriage after being turned. The cants are then lowered to their horizontal position, by raising the lever K, which causes the trippers L L to disengage the shoulders G of the connecting-rods F F from the toes of the cams E E, thus causing the connecting-rods F F to slide forward, and thereby lowering the canting-levers H and the cants I to their proper positions.

What I claim as my invention, and desire to secure by Letters Patent, is—

1. The reciprocating rod F, provided with shoulder G, operated by the hook-lever E, and actuating the canting-lever H, in combination with the cant I, when constructed and operating as described.

2. The combination of the cants I, canting-levers H, shaft B, connecting-rods F, with shoulders G, shaft J, lever K, trippers L, and pins M, all arranged substantially as and for the purposes set forth.

ISAAC H. NEWTON.
